UNITED STATES PATENT OFFICE

2,678,473
TOP ROLL FOR TEXTILE DRAWING
MECHANISMS

Richard K. Butler, Whitman, Mass., assignor, by
mesne assignments, to Textile Engineering Cor-
poration, Whitman, Mass., a corporation of
Massachusetts

Application August 19, 1948, Serial No. 45,045

1 Claim. (Cl. 19—142)

1. The so-called "solid top rolls" used in textile drawing mechanisms usually comprise a cast-iron or steel body provided with two enlargements or bosses connected by a reduced or neck portion and also with journals or gudgeons projecting from the outer ends of the bosses. When such a roll is in-use the bosses are covered with cots which may be made of leather, synthetics, or other non-metallic materials usually having a substantial degree of resiliency. These cots ride on the lower-fluted roll with which the top roll cooperates where they press the strands of roving or sliver against the bottom roll as the drawing operation proceeds, and the weight required for this purpose is applied through a saddle which bears on the neck of the roll. In order to hold the roll against travel either backward or forward, the gudgeons are positioned in slots formed in cap bars located at opposite sides of each set of top rolls. The foregoing is an arrangement used almost universally in spinning and roving frames.

One of the objectionable features of rolls of this character is the fact that the bearing or friction surfaces of the roll body, namely the gudgeons and the necks, soon become worn to such a degree that the entire roll must be discarded. While this has always been regarded as a necessary incident to manufacturing procedure, it is a serious factor in view of the expense of production of these bodies.

Another troublesome feature of such constructions is the further fact that frequent cleaning is necessary to remove the lint and fly which collects on the roll necks and gudgeons and in the slots of the cap bars. Usually, also, the neck portions, and often the gudgeons as well, must be lubricated, although care should be taken to use the lubricant sparingly, both because it makes cleaning more difficult and also for the reason that any spot or film of oil on the cots or on the fibrous material being drafted is highly objectionable.

The present invention aims to devise a top roll construction in which these objectionable features will be eliminated.

The nature of the invention will be readily understood from the following description when read in connection with the accompanying drawings, and the novel features will be particularly pointed out in the appended claim.

In the drawing,

Fig. 1 is a front elevation of a roll constructed in accordance with this invention; and

Fig. 2 is a vertical, sectional view of the roll

is available in both tubular and solid rod forms and can either be molded or machined to the desired shape and dimensions. Compositions having a high tensile strength ample for the purposes of this invention are obtainable from the concern above mentioned.

Another synthetic composition which may be substituted for nylon with satisfactory results, although more expensive and somewhat more difficult to obtain, is that known as "Teflon." 10 This is defined chemically as a polytetrafluorethylene polymer and is also obtainable from the DuPont Company. This material is the equivalent of nylon for the purposes of this invention.

The other synthetic thermoplastics above mentioned can also be substituted for the nylon and Teflon just described, and used without the addition of lubricants. This is also true of the self-lubricating materials above referred to, one example of which is obtainable commercially under 20 the name of "Oilite." All of these materials have the important operating advantage afforded by their extremely low coefficient of friction.

It has been common to run cast-iron rolls of the character above described with cast-iron 25 saddles and in cast-iron bearings, or cap-bars. Once a glaze is established on the friction surfaces the parts operate quite satisfactorily. The coefficient of cast-iron running on cast-iron slightly lubricated is given in Machinery's Handbook as .15. All of the materials above mentioned which applicant proposes to use in the construction of his roll body have a very much lower coefficient of friction which translates itself into a saving in power and a consequent reduction in overhead costs. Moreover, because no lubricant is required, both the labor and expense for applying it and the work involved in cleaning is reduced very materially. While some of the materials mentioned are not suited to high 30 speed operation, others do not have this limitation.

The invention thus provides a top roll of the solid type which is far superior to those in common use, not only because it requires no lubrication, but also due to the fact that less power 45

is required to drive it and the expenses of operation and renewal are reduced.

Having thus described my invention, what I desire to claim as new is:

5 A top roll for the textile drawing mechanisms of spinning and roving frames, comprising a shaft, two bosses supported on said shaft and adapted for the application thereto of the customary cots, said bosses having a pressed fit upon said shaft and being spaced apart, and gudgeons pressed into the outer ends of said bosses beyond the ends of the shaft.
